CLAIM

The ornamental design for a portion of a shoe upper, as shown and described.

DESCRIPTION

FIG. 1 is a perspective view of a portion of a shoe upper showing my new design;
FIG. 2 is a side elevational view of one side thereof;
FIG. 3 is a front elevational view thereof;
FIG. 4 is a rear elevational view thereof;
FIG. 5 is a top plan view thereof; and,
FIG. 6 is a side elevational view of the other side thereof. The uneven broken line immediately adjacent to the shaded area represents a boundary of the claimed design. The uneven broken line showing the remainder of the shoe is for illustrative purposes only and forms no part of the claimed design.
